CLAIM

The ornamental design for a medical device clip or the like for attaching a surgical wound drainage evacuator or the like to various sites, as shown and described.

DESCRIPTION

FIG. 1 is a perspective view of a medical device clip or the like for attaching a surgical wound drainage evacuator or the like to various sites showing my new design; FIG. 2 is a side elevational view thereof, in open position;

FIG. 3 is a side elevational view thereof;

FIG. 4 is a front end elevational view thereof; and

FIG. 5 is a top plan view thereof.
